STOPPER AND METHOD OF MAKING
THE SAME

Alfred R. Mottur, Brooklyn, N. Y.

Application December 3, 1937, Serial No. 177,910

4 Claims. (Cl. 215—48)

This invention relates to stoppers for bottles and other containers and the method of manufacturing the same, an object being to provide a simplified method for pressing the parts of a stopper in place ready for use.

Another object of the invention is to provide a stopper with a head formed with a compressed peripheral part adapted to pinch the disk for holding the same in place.

10 A further object is the provision of an improved method wherein by successive steps a metal disk or disk of other material is pressed into a piece of wood and the wood caused to flow over the peripheral edge of the disk so as to hold 15 the same in place.

In the accompanying drawing—

Fig. 1 is a longitudinal vertical section through parts of a die structure used in forming the head of a stopper according to the present invention; 20 Fig. 2 is a view similar to Fig. 1 but showing the pressing operation completed;

Fig. 3 is a transverse sectional view through the stopper after it has been formed;

Fig. 4 is a top plan view of the structure shown 25 in Fig. 3;

Fig. 5 is an enlarged fragmentary sectional view similar to the left-hand part of Fig. 2, illustrating how the parts press the grain of wood extending from the obverse to the reverse face 30 of the head;

Fig. 6 is a sectional view similar to Fig. 1 but showing the first step in the construction of a modified form of structure to that illustrated in Fig. 3;

35 Fig. 6a is a view similar to the left-hand part of Fig. 6 but showing the parts in an advanced position;

Fig. 7 is a view similar to Fig. 6 but showing a different die structure for completing the pressing operation;

Fig. 8 is a view similar to Fig. 3 but showing the construction of head illustrated in Fig. 7;

Fig. 9 is an enlarged fragmentary sectional view of the left-hand part of Fig. 7 and illustrating how the wood is caused to flow over and bend down the edge of the disk;

Fig. 10 is a view similar to Fig. 3 but showing a modified structure wherein a plurality of disks of any desired material are forced into the depressions and held therein by friction.

Referring to the accompanying drawing by numerals, 1 indicates part of a die designed to receive a plunger 2. An ejecting plate 3 is arranged in die 1 and may be actuated through a stem 4 by any desired means for forcing the

wooden head 5 out of the die after the pressing operation has been completed. It will be noted that the plunger 2 is provided with notches 6 and 7 whereby the extension 8 is of the same size as the disk 9. This disk is preferably made 5 of metal and is pressed directly into the wooden head 5 as shown in Fig. 2. The head 5 may be of any desired shape but is preferably circular and the grain 10 extends vertically as shown in the drawing, or from the obverse to the reverse 10 face. By a single operation the disk 9 is positioned in a depression in the obverse face of the head 5. When compressing the wood, as shown in Fig. 2, the die 1 prevents any expansion and, consequently, the head is condensed 15 or pressed particularly around the peripheral part whereby the peripheral part will fit the edge of the disk 9 and hold the same in place. By compressing the inner part or wall 5' more than the outer part or wall 5'' there is produced an 20 inward pressure or tension on the disk 9 while the part or outer wall 5'' prevents bulging or expansion outwardly at this point. The disk 9 may be provided with advertising or other matter without departing from the spirit of the invention. 25

After the head 5 has been constructed as just described, a body 11 is secured thereto in any desired manner, preferably by glue. The body 11 may be wood or other material, but is preferably cork. The head 5 forms a desirable hand hold 30 for applying and removing the body 11 when the stopper is in use.

In Fig. 6 a modified form of plunger 2' is shown wherein there is a central extension 8' and a single notch 13. By reason of this structure one 35 or more disks 9' may be pressed directly into the wooden head 5 leaving an annular projection 14 surrounding the disk. After the operation shown in Fig. 6 has been completed, the plunger 2' is removed and a plunger 2'' is moved downwardly 40 and presses against the disk or disks 9' for holding the same in place while the plunger die 15 functions. It will be noted that this die is provided with an offset part 16 and a pressing part 17. As this portion of the plunger presses against 45 the upstanding part 14 it compresses the same and causes the inner part of the annular upstanding part 14 to overflow and form a bead 18. At the same time, the bead 18 is compressed to such an extent that the peripheral edge portion 50 19 of disk 9' will be depressed as shown in Fig. 9. It will be seen from Figs. 6 and 7 that the plunger 2'' is of less diameter than the extension 8' so that after the plunger 2'' is in position as shown in Fig. 7, there will be a space between the plung- 55

er and the annular upstanding part 14. However, when the plunger die 15 moves downwardly to the position shown in Fig. 7 it will compress the entire upstanding part 14 and cause part to 5 overflow and fill up the space so that the finished product will be as shown in Fig. 9. After the disk 9' has been completed as just described the head 5 is removed and the cork body 11 secured 10 in place by glue or other adhesive. When the stopper is completed it will appear as shown in Fig. 8.

In Fig. 10 a further modified structure is shown which is similar to that shown in Fig. 3, but the modification merely consists of the provision of 15 a deeper depression 20 so as to receive a plurality of disks 21 which are held in place by friction against their peripheral edge.

I claim:

1. A stopper comprising a cork body, a wooden 20 head formed with an inwardly extending bead, and a metal disk countersunk in the upper face of the head and positioned to be overlapped by said bead.

2. A stopper comprising a body, a wooden head and a disk countersunk in the upper face of the head, said head having an integral annular flange overlapping the edge of said disk.

3. A stopper comprising a body, a wooden head having a central depression in its obverse face, and a disk fitting in said depression with the edge bent slightly downwardly, said edge being embedded wholly in said head.

4. A stopper comprising a body, a disk-shaped 10 wooden head formed with the grain thereof extending from the obverse to the reverse face, said head having a centrally positioned depression, and a disk positioned flatwise in said depression, the material of said head being more dense at the 15 peripheral edge of said depression than at the remaining part of the head and positioned to pinch said disk so as to hold the disk frictionally against removal.

ALFRED R. MOTTUR. 20
